(57) **CLAIM**

The ornamental design for a hook attachment device, as shown and described herein.

DESCRIPTION

FIG. 1 is a perspective view of a hook attachment device showing the new design;

FIG. 2 is a right side elevational view thereof;

FIG. 3 is a left side elevational view thereof;

FIG. 4 is a front side elevational view thereof;

FIG. 5 is a back side elevational view thereof;

FIG. 6 is a bottom plan view thereof;

FIG. 7 is a perspective view of the hook attachment device shown in FIG. 1 with a top portion thereof rotated ninety degrees;

FIG. 8 is a right side elevational view of FIG. 7;

FIG. 9 is a left side elevational view of FIG. 7;

FIG. 10 is a front side elevational view of FIG. 7;

FIG. 11 is a back side elevational view of FIG. 7; and,

FIG. 12 is a bottom plan view of FIG. 7.

The broken line portions of the disclosure are for illustrative purposes only and form no part of the claimed design.
